UNITED STATES PATENT OFFICE.

GEORGE G. FRYER, OF SYRACUSE, NEW YORK, ASSIGNOR TO SEMET SOLVAY COMPANY, OF SYRACUSE, NEW YORK, A CORPORATION OF PENNSYLVANIA.

CAR.

934,398.

Specification of Letters Patent. Patented Sept. 14, 1909.

Original application filed March 24, 1902, Serial No. 99,805. Divided and this application filed December 30, 1905. Serial No. 293,881.

To all whom it may concern:

Be it known that I, GEORGE G. FRYER, of Syracuse, in the county of Onondaga and State of New York, have invented a certain 5 new and useful Car, of which the following is a specification.

My invention has for its object the production of a car, particularly applicable for use in the coke-handling apparatus forming 10 the subject-matter of my pending application, Sr. No. 99,805, filed March 24, 1902; and to this end it consists in the combinations and constructions hereinafter set forth and claimed.

15 In describing this invention, reference is had to the accompanying drawing in which like characters designate corresponding parts in all the views.

Figures 1 and 2 are, respectively, a plan 20 and an elevation of a preferable construction of my car. Figs. 3 and 4 are, respectively, a plan and an elevation, partly in section, of the support for the platform of my car.

25 This car comprises, generally, a frame 1 and a movable platform 2.

The frame 1 may be of any desirable form, size and construction, is formed with a depending arc-shaped member 3, and is 30 suitably mounted on trucks 4.

The platform 2, as here shown, is circular in form, and is so mounted on the frame as to be moved relatively thereto about axes arranged at an angle to each other. As illustrated, the platform is rotatable on a substantially upright axis, relatively to a support 5 which is journaled in the frame on a substantially horizontal axis extending lengthwise of the frame, said support being 35 formed with a vertical bearing 6 in which a spindle 7 provided on the platform is journaled, and also with trunnions 8 journaled in bearings provided in the frame. Thus the platform may move relatively to the 40 frame about substantially horizontal and upright axes.

50 Preferably, the platform and support are provided respectively, with annular bearing-faces 9, 10 encircling the base of the spindle 7 and the upper end of the bearing 6, and the lower end of the spindle engages the arc-shaped member 3 and thereby relieves the

trunnions 8 of some of the weight of the platform. Said support is also formed with a rack 11, and with a laterally-extending 55 arm 12 having a journal-bearing 13 at its outer end, and said platform is provided with a circular rack 14 preferably disposed on its lower side.

The means for moving the support relatively to the frame and the platform relatively to the support, and thereby moving the platform on its horizontal and vertical axes, comprise revoluble elements 15 and 16 journaled, respectively, in the frame 1 and 60 in the bearing 13 formed in the arm 12 of the support 5, and pinions 17 and 18 carried by said elements 15 and 16 and meshing, respectively, with the racks 11 and 14.

A wall 19 is usually provided about the 65 platform, this wall 19 being preferably fixed to the frame and supported thereon in any suitable manner as by braces 20. A portion of said wall is provided with a floor 21, and gate 22, the floor being flush with the platform when the latter is in horizontal position, and the gate being arranged at one side of the vertical axis of the platform.

When my car is used with a coke-handling apparatus forming the subject-matter of my 80 aforesaid patent, the coke emerges in a compact mass or body from the coke-oven and moves through the gateway upon the platform 2 with a minimum breakage. The movement of the coke upon the platform 2 85 may serve to rotate the platform in order to constantly bring an unoccupied space of the platform to the gateway, until the platform is loaded, or if desired, the element 16 may be operated for this purpose. When 90 the coke is discharged upon the platform, it is quenched in any suitable manner and is conveyed to the point of use by the car, when it may then be discharged from the car by tilting the platform by operating the element 15 so that the coke is free to slide from the platform under the wall 19. Although 95 my car is applicable for use as a car for said coke-handling apparatus, it will be understood by those skilled in the art that it may serve other purposes.

What I claim is:—

1. In a car, the combination of a frame provided with an arc-shaped member, and a

- platform journaled in the frame and provided with means coöperating with said member for supporting the platform, substantially as and for the purpose described.
- 5 2. In a car, the combination of a frame, a support mounted on the frame and movable about an axis relatively thereto, revoluble means for moving the support, said means being journaled in the frame and coöperating with the support, and a platform mounted on the support and movable about an axis disposed at an angle to the axis of the support, substantially as and for the purpose described.
- 10 3. In a car, the combination of a frame, a support journaled in the frame and movable relatively thereto about a substantially horizontal axis, said support being formed with a substantially upright bearing and an annular bearing face surrounding the upper ends of the said bearing, and a platform mounted on the support and having a spindle journaled in the bearing, and an annular bearing face at the base of the spindle for co-operating with the first-mentioned bearing face, substantially as and for the purpose specified.
- 15 4. In a car, the combination of a frame, a support mounted on the frame and movable about an axis relatively thereto, a platform mounted on the support and movable about an axis disposed at an angle to the axis of the support, and means carried by the support for moving the platform about its axis, substantially as and for the purpose set forth.
- 20 5. In a car, the combination of a frame, a support mounted on the frame and movable about an axis relatively thereto, means carried by the frame for moving the support about its axis, a platform mounted on the support and movable about an axis disposed at an angle to the axis of the support, and means carried by the support for moving the platform, substantially as and for the purpose described.
- 25 6. In a car, the combination of a frame, a support journaled in the frame and movable relatively thereto about a substantially horizontal axis, said support having a laterally-extending arm provided with a bearing at its outer end, a platform journaled in the support and movable relatively thereto about a substantially upright axis, and means for moving the platform about its axis, said means being journaled in the bearing provided on the laterally-extending arm of the support, substantially as and for the purpose specified.
- 30 7. In a car, the combination of a frame, a support mounted on the frame and movable about an axis relatively thereto, said support having a rack and a laterally-extending arm provided with a bearing at its outer end, revoluble means for moving the support, 65 said means being journaled in the frame, a platform mounted on the support and movable about an axis disposed at an angle to the axis of the support, and revoluble means for moving the platform, the last-mentioned means being journaled in the bearing provided on the laterally-extending arm of the support, substantially as and for the purpose set forth.
- 35 8. In a car, the combination of a frame, a support journaled in the frame and movable relatively thereto about a substantially horizontal axis, a platform journaled in the support and movable relatively thereto about a substantially upright axis, and means for 70 additionally supporting the platform for relieving the support, substantially as and for the purpose described.
- 40 9. In a car, the combination of a frame having an arc-shaped engaging-face, a support mounted on the frame above the engaging-face and journaled in the frame movable about a substantially horizontal axis, said support being formed with a substantially upright bearing, a platform 75 mounted on the support and provided with a spindle journaled in the upright bearing of the support, said spindle having its lower end engaged with the arc-shaped face provided on the frame, substantially as and for the purpose specified.
- 45 10. In a car, the combination of a frame having an arc-shaped engaging-face, a support mounted on the frame above the engaging-face and journaled in the frame and movable about a substantially horizontal axis, said support being formed with an upright bearing, and an annular bearing-face surrounding the upper end of the upright bearing, a platform mounted on the support 80 and provided with a spindle journaled in the upright bearing, and with an annular bearing-face surrounding the base of the spindle, for engaging the annular bearing-face provided on the support, and said spindle having its lower end engaged with the arc-shaped face provided on the frame, substantially as and for the purpose set forth.
- 50 11. In a car, the combination of a frame, a support mounted on the frame and movable about an axis relatively thereto, a platform mounted on the support and movable about an axis disposed at an angle to the axis of the support, and a wall encircling the platform, said wall being supported by 85 the frame and fixed thereto, substantially as and for the purpose described.
- 55 12. In a car, the combination of a frame, a support mounted on the frame and movable about an axis relatively thereto, a platform mounted on the support and movable about an axis disposed at an angle to the axis of the support, and a wall encircling 90
- 60 13. In a car, the combination of a frame, a support mounted on the frame and movable about an axis relatively thereto, a platform mounted on the support and movable about an axis disposed at an angle to the axis of the support, and a wall encircling 95
- 65 14. In a car, the combination of a frame, a support mounted on the frame and movable about an axis relatively thereto, a platform mounted on the support and movable about an axis disposed at an angle to the axis of the support, and a wall encircling 100
- 70 15. In a car, the combination of a frame, a support mounted on the frame and movable about an axis relatively thereto, a platform mounted on the support and movable about an axis disposed at an angle to the axis of the support, and a wall encircling 105
- 75 16. In a car, the combination of a frame, a support mounted on the frame and movable about an axis relatively thereto, a platform mounted on the support and movable about an axis disposed at an angle to the axis of the support, and a wall encircling 110
- 80 17. In a car, the combination of a frame, a support mounted on the frame and movable about an axis relatively thereto, a platform mounted on the support and movable about an axis disposed at an angle to the axis of the support, and a wall encircling 115
- 85 18. In a car, the combination of a frame, a support mounted on the frame and movable about an axis relatively thereto, a platform mounted on the support and movable about an axis disposed at an angle to the axis of the support, and a wall encircling 120
- 90 19. In a car, the combination of a frame, a support mounted on the frame and movable about an axis relatively thereto, a platform mounted on the support and movable about an axis disposed at an angle to the axis of the support, and a wall encircling 125

the platform, said wall being supported by the frame and fixed thereto, and a portion thereof being formed with a floor and with a gateway, substantially as and for the purpose specified.

In testimony whereof, I have hereunto signed my name in the presence of two at-

testing witnesses at Syracuse, in the county of Onondaga, in the State of New York, this 28th day of December, 1905.

GEORGE G. FRYER.
